UNITED STATES PATENT OFFICE

2,667,276

DEVICE FOR TRANSFERRING INGOT
MOLD CAPSAlden W. Peterson, Lorain, Ohio, assignor to
United States Steel Corporation, a corporation
of New Jersey

Application May 8, 1951, Serial No. 225,138

2 Claims. (Cl. 212—4)

1

This invention relates to a device for transferring ingot mold caps between an ingot mold and a supporting platform.

An object of the invention is to provide a readily portable, rugged and simple device for transferring ingot mold caps in either direction between a mold and a supporting platform.

A further object is to provide a cap transferring device which includes a member adapted to bridge the space between an ingot mold and a pouring platform and a trolley riding thereon and adapted to engage a mold cap for carrying the cap in either direction between the mold and the pouring floor.

A further object is to provide a cap transferring device which eliminates the need to use cranes for this purpose, but makes possible the transfer of caps by a simple portable trolley device.

In accomplishing these and other objects of the invention, I have provided improved details of structure, a single form of which is shown in the accompanying drawings, in which:

Figure 1 is a side elevational view, partly in section, showing a portion of an ingot mold and a pouring floor and a cap transferring device constructed according to the present invention in position for engaging or releasing a cap over the mold;

Figure 2 is a view similar to Figure 1, but showing the transferring device in position for engaging or releasing the cap over the floor; and

Figure 3 is a top plan view of the cap transferring device.

Figures 1 and 2 show in vertical section portions of an ingot mold 10 and a pouring platform 12 spaced therefrom. The mold has a cap 13 which commonly weighs in excess of 200 pounds and must on occasion be transferred between the mold and the floor. The cap carries a suitable lifting eye 13a.

The transferring device of the present invention comprises an elongated trolley rod 14 which is adapted to bridge the space between the mold and the pouring platform. Said rod has a shallow U-shaped bend 15, which is situated intermediate its ends and forms a delivery notch, and a sharp bend 16, which is situated adjacent its platform end and forms a supporting leg 17 adapted to rest on the platform. A handle 18 is rigidly attached to rod 14 adjacent its bend 16. The mold end of rod 14 carries upper and lower longitudinal reinforcing plates 19 and 20 respectively, a U-shaped main yoke 21 and a

2

U-shaped brace yoke 22, all welded together to form a rigid structure adapted to rest on the upper face of the mold. Indexing fingers 23 and 24 are pivoted to the lower extremities of the main yoke, and have hook portions 25 adapted to engage the edge of the mold.

A trolley 26 is mounted on rod 14. The inner end of the upper reinforcing plate 19 is notched to form a stop 27. Trolley 26 can ride along rod 14 between the stop formed by the bend 15 and the stop 27. Preferably the trolley includes a roller 28, a hook 29 adapted to engage the lifting eye of the mold cap, and a handle 30. Where it is desired to retard movement of the trolley frictionally, the roller can be omitted.

In operation, assume first that it is desired to remove cap 13 from mold 10 and transfer this cap to the pouring platform 12. The cap first is loosened in the conventional way. The transferring device just described, which is of light weight and easily portable, is placed across the space between the mold and the platform with the main yoke 21 resting on top of the mold and the hook portions 25 of the indexing fingers 23 and 24 engaged over the edge of the mold. Handle 18 is lifted manually and trolley 26 moves down trolley rod 14 toward the mold end until it engages stop 27, as shown in full lines in Figure 1. The parts are proportioned so that in this position the trolley is approximately centered over the mold cap 13. Next hook 29 is engaged with the lifting eye 13a of said cap.

Next the platform end of the trolley rod 14 is forced down manually until its leg 17 rests on the platform 10, as shown in dotted lines 35 in Figure 1 and full lines in Figure 2. Trolley 26, carrying cap 13, moves gravitationally along the rod toward said platform until it engages delivery notch 15. The parts are proportioned 40 so that cap 13 now rests on the platform and the transferring device can be removed to be used elsewhere.

When it is desired to transfer a cap from the pouring platform to the mold, the movements 45 just described are reversed. That is, the main yoke 21 and indexing fingers 23 and 24 are engaged with the mold and the hook 29 with the lifting eye of the cap, which now is resting on the platform. Handle 18 is lifted manually and trolley 26, carrying the cap, moves gravitationally down the rod until it engages stop 27. The cap now is centered over the mold. Hook 29 next is disengaged from the lifting eye, and the device 50 can be removed for use elsewhere.

From the foregoing description, it is seen that

the present invention affords a simple and practical device for transferring ingot mold caps in either direction between an ingot mold and a pouring platform. The device eliminates the need for using cranes for this purpose, and thus releases such cranes for other uses.

While I have shown and described only a single embodiment of the invention, it is apparent that modifications may arise. Therefore, I do not wish to be limited to the disclosure set forth but only by the scope of the appended claims.

I claim:

1. A device for transferring ingot mold caps between an ingot mold and a pouring platform comprising an elongated member adapted to bridge the space between a mold and a platform, a downwardly depending yoke connected at its upper end to said member adjacent one end of the latter, the lower end of said yoke being adapted to rest on the top of the mold, indexing fingers pivoted to said yoke adjacent the lower end thereof and adapted to engage over an upper edge of the mold, a leg connected at its upper end to said member adjacent the other end thereof, the lower end of said leg being adapted to rest on the platform, spaced apart stop means on said member, a trolley mounted on said member for movement therealong between said stop means, and a hook carried by said trolley and adapted to engage a mold cap.

2. A device for transferring ingot mold caps

between an ingot mold and a pouring platform comprising an elongated rod having a shallow U-shaped bend intermediate its length, a downwardly depending yoke connected at its upper end to said rod adjacent one end of the latter, the lower end of said yoke being adapted to rest on the top of the mold, indexing fingers pivoted to said yoke adjacent the lower end thereof and adapted to engage over an upper edge of the mold, a leg connected at its upper end to said rod adjacent the other end thereof, the lower end of said leg being adapted to rest on the platform, stop means on said rod adjacent its connection with said yoke, a trolley mounted on said rod for movement therealong between said bend and said stop means; and a hook carried by said trolley and adapted to engage a mold cap.

ALDEN W. PETERSON.
